(57) **CLAIM**

The ornamental design for a pedicure basin base as shown and described.

DESCRIPTION

FIG. 1 is an upper perspective view of the pedicure basin base according to my design;

FIG. 2 is a front elevation view thereof;

FIG. 3 is a back elevation view thereof;

FIG. 4 is a top plan view thereof;

FIG. 5 is a bottom plan view thereof;

FIG. 6 is a side elevation view thereof, the opposite side elevation view being a mirror image thereof; and,

FIG. 7 is a bottom perspective view thereof.

The broken lines in the drawings illustrate portions of the pedicure basin base that form no part of the claimed design.

1 Claim, 3 Drawing Sheets
